(57) CLAIM

The ornamental design for an outdoor fireplace, as shown and described.

DESCRIPTION

FIG. 1 is a top right front perspective view of an outdoor fireplace showing our new design.

FIG. 2 is a top left front perspective view of the outdoor fireplace of FIG. 1;

FIG. 3 is a bottom right front perspective view of the outdoor fireplace of FIG. 1; and,

FIG. 4 is a bottom left front perspective view of the outdoor fireplace of FIG. 1.

The broken line showing of decorative panels is for illustrative purposes only and forms no part of the claimed design.

UNITED STATES PATENT AND TRADEMARK OFFICE
CERTIFICATE OF CORRECTION

PATENT NO. : Des. 515,680 S
DATED : February 21, 2006
INVENTOR(S) : James Borowske et al.

Page 1 of 6

It is certified that error appears in the above-identified patent and that said Letters Patent is hereby corrected as shown below:

Replace title page with attached title page.

Replace figures 1 through 4, with those printed on sheets 1 through 4, attached.

Signed and Sealed this

Thirtieth Day of May, 2006

A handwritten signature in black ink, appearing to read "Jon W. Dudas". The signature is written in a cursive style with a large, stylized "J" and "D".

JON W. DUDAS
Director of the United States Patent and Trademark Office
